CAPACITY-TYPE PHONOGRAPH PICKUP

Frank B. Tatro, Chicago, Ill., assignor, by mesne assignments, to Virgil A. Hamilton, Chicago, Ill.

Application April 10, 1941, Serial No. 387,792

2 Claims. (Cl. 179—100.41)

1

This invention relates to a radio-phonograph and more particularly to the phonographic "pick-ups" and the circuits connecting such "pick-ups" to the radio or electronic amplifying and reproducing circuits.

It is an object of my invention to provide an improved apparatus for reproducing sound from phonograph records or the like.

A further object of the invention is to provide a phonograph record "pick-up" having a higher signal to noise ratio and an improved frequency response to the higher audio frequencies and provide suitable amplifying circuits controlled by said "pick-up."

A further object of the invention is to provide an improved radio-phonograph and an improved phonograph pick-up which may be manufactured at materially less cost, but which at the same time possesses greater fidelity and quality in the reproduction of all frequencies within the audio range.

A more specific object of the invention is to provide in a radio-phonograph or a phonograph, circuits connecting the phonographic pick-up to a local oscillator of a superheterodyne radio receiving or reproducing circuit whereby impedance, i. e., capacity varying phonographic pick-ups may be employed to effect a frequency or amplitude modulation of an "intermediate frequency" voltage which is then fed to a detector and an audio amplifier.

Other and further objects and advantages of the invention will be apparent from the following description when taken in connection with the accompanying drawings, wherein:

Figure 1 is a fragmentary view in perspective illustrating a phonographic tone arm carrying a capacity varying pick-up forming part of the present invention;

Figure 2 is an enlarged fragmentary view in section taken substantially along the line 2—2 of Figure 1;

Figure 3 is an enlarged end view of the capacity pick-up of Figures 1 and 2;

Figure 4 is a schematic diagram of a superheterodyne radio receiver circuit and its connection to the capacity pick-up of Figures 1 to 3;

Figure 5 is a schematic diagram illustrating the manner of connection of a variable resistance pick-up to the local oscillator of a superheterodyne receiver;

Figure 6 is a view of a rheostat which may be used in the resistance pick-up schematically illustrated in Figure 5;

Figure 7 is a schematic circuit diagram show-

2

ing the connection of a variable inductance pick-up to a local oscillator which may be used remotely from a reproducing radio receiver or which may be part of the radio receiver;

5 Figure 8 is a view in vertical section through a variable inductance pick-up which may be used with the circuit of Figure 7;

Figure 9 is a view in vertical section of another form of variable inductance pick-up which may be used with the circuit of Figure 7;

10 Figure 10 is a schematic drawing of the connection of the windings of the single tapped coil forming the inductive pick-up of Figure 9;

Figure 11 is a view in vertical section of another 15 form of inductive pick-up which may be used with the circuit of Figure 7;

Figure 12 is a schematic drawing of the interconnection of the coils of the pick-up shown in Figure 11;

20 Figure 13 is a schematic diagram illustrating the connection of a variable inductance pick-up to a combined local oscillator-converter of a superheterodyne radio receiver;

Figure 14 is a schematic diagram illustrating 25 the connection of a variable capacity pick-up to a local oscillator for effecting amplitude modulation of the local oscillations; and

Figure 15 is a schematic diagram similar to 30 Figure 14, but showing the connection of a variable resistance pick-up to the local oscillator.

Phonographic pick-ups in commercial use are 35 relatively expensive to manufacture and have a limited frequency response. They generally emphasize the lower audio range and have a tendency to attenuate the frequencies in the band from 2000 to 5000 cycles. This is the ordinary scratch or noise range of records played at the usual speed of 33 1/3 or 78 R. P. M. Consequently such pick-ups have a relatively low signal to noise ratio and 40 it is therefore necessary in reproducing the range of frequencies from 2000 to 5000 cycles to further attenuate the signals within this range in order to eliminate noise frequencies or to amplify and reproduce the noise frequencies along with these 45 lower audio frequencies. This results either in the elimination of the desired audio frequencies within this range, or in the unwanted reproduction of the noise frequencies.

Applicant has found that this undesirable characteristic of attenuation of the lower audio frequencies is characteristic of all pick-ups which generate voltages from the mechanical vibrations of a needle traversing a record groove.

Applicant has also found that it is impossible 55 to reproduce these generated audio-frequency

voltages with fidelity by means of direct amplification, of the audio-frequency voltages. In seeking to overcome these difficulties of present phonographic pick-ups and reproducing circuits, applicant has found that by means of the invention, if an impedance varying or voltage varying pick-up, as distinguished from a voltage generating pick-up, is used to convert the undulations of the sound record into electrical variations and such variations are used to effect the frequency or amplitude modulations of a locally generated oscillation such as produced in a super-heterodyne receiver, the fidelity of response to all audio-frequencies is greatly improved and audio or acoustical frequencies within the scratch or noise range of frequencies may be reproduced with clarity, and further that all this may be accomplished by means of devices and circuits which may be manufactured at a cost less than the cost of the present type of pick-ups and reproducing circuits.

As shown in Figure 1, the tone arm 2 which may be of conventional construction and mounted in the usual manner, carries at its outer free end a capacity pick-up 4 which may comprise a block 6 of suitable insulating material secured to the tone arm in any desired manner as, for example, by means of the bracket 8 fixed to the tone arm and screws or bolts 10 passing through the block 6 and received in the bracket 8. The tone arm 2 is hollow as is conventional, and the pick-up 4 is housed within the arm and the necessary leads pass through the hollow arm from the free end to the opposite end and pass from the arm adjacent to or through the pin or pivot on which the arm is mounted. The capacity pick-up 4 comprises in addition to the block 6 a plurality of thin metal plates 12 separated by layers 14 of dielectric material which may comprise strips of relatively soft rubber or may comprise coatings or strips of any suitable dielectric material. The plates 12 are made of such material and of such thickness or mounted in such manner that they may be readily moved or flexed toward and from each other by means of a needle as 16 secured to the outer plate 12, the needle traversing the sound grooves of the record 18 shown in Figure 1.

The needle 16 may be soldered to the outer plate 12, or it may be received in a suitable light needle holder mounted on this plate. The clamping screw 20 passes through enlarged central openings in the plates 12 and is received in a nut 22 mounted in the block 6. One or more strips or washers 24 of insulating material such as soft rubber insulate the head of the screw 20 from the outer plate 12. The strips 14 which may be of a plastic cushioning material or sponge rubber cushion the plates and minimize resonant frequencies that the assembly may have so that the assembly will not resonate mechanically at a frequency within the audio range. The number of plates, the dimensions of plates, the thickness and kind of insulating or dielectric material used between the plates, and the pressure applied to the plates with the clamping screw all determine the sensitivity and frequency of response of the pick-up 4.

The pick-up device being sensitive to side-to-side, or lateral, movements and relatively insensitive to up and down movements, capacity variations are produced only by the lateral undulations of the record grooves, or side-to-side movements of the stylus.

One lead 26 (Figure 4) from the pick-up 4 may

be grounded while the other and shielded lead 28 extends to the contact point 30 of a switch 32 by which it may be connected to the superheterodyne radio receiver 34 of a combined radio-phonograph. The switch 32 connects the phonograph lead 28 to the circuits of the local oscillator or mixer tube 36. The tube 36 comprises a plate 38, a screen grid 40, an oscillator anode 42, an oscillator grid 44, and a control grid 46. The out-put or plate circuit of the tube 36 is coupled to the in-put of an intermediate frequency amplifier tube 48 by means of the doubly tuned transformer coupling 50 tuned to the intermediate frequency. The primary 52 of this transformer is tuned by the condenser 54 and the secondary 56 is tuned by the condenser 58. The plate 38 is connected to the positive direct current supply terminal 60 through the primary 52 and the wire 62. The screen grid 40 is connected to this terminal through the resistance 64 and the oscillator anode 42 is connected to this same terminal through the resistor 66.

The cathode 68 is connected to ground through the self-biasing resistor 70 and the by-pass condenser 72. The screen grid is maintained at ground potential with respect to radio frequency voltages through the condenser 74. The filament 76 for the cathode may be energized from the ordinary low voltage filament circuit of the radio receiver supply circuit. The oscillator anode 42 is coupled to the grid 44 when the ganged switches 32 and 78 are in the position shown in Figure 4 through the wire 80, the blocking condenser 82, the wiper 84 of the switch 78, the switch contact 86, the wire 88, the feed-back coupling transformer 92, the wire 94, the wiper 96 of the switch 32, the wire 98, the grid condenser 100 and the wire 102. The grid condenser 100 is shunted by the resistor 104 and the tuning condenser 106 as is conventional.

The control grid 46 is connected by the wire 108 to the radio frequency coils and band switch of the radio frequency amplifying part of the radio receiver, the band switch which is conventional and not shown, being ganged to the switches 32 and 78 so that with the switches 32 and 78 in the position shown in Figure 4 and the R. F. band switch in a corresponding setting, the local oscillator or mixer tube 36 will be set to oscillate at the proper frequency to produce in the output circuit of the tube 36 the desired intermediate frequency signals. With the switches 32 and 84 in position connecting the wipers 96 and 84 to the short wave contacts 110 and 112, the oscillator anode is coupled to the grid through the short wave feed-back coupling transformer 114, the secondary of this short wave coupling transformer being connected to the switch point 110 by the wire 116 and the primary connected to the switch point 112 by the wire 118. With the wiper 96 in position to engage the contact 30, the phonograph lead 28 is connected by the wiper 96 to the grid lead 98 and to the contact point 120 which is connected by the wire 122 and the wire 94 to the secondary of the broadcast frequency transformer 92. The wiper 84 of the switch 78 at this time through the contact 124 and the wires 126 and 88 connects the primary of this broadcast frequency transformer 92 to the oscillator anode wire 80 through the blocking condenser 82. The mechanical variations transmitted by the needle 16 from the lateral undulations of the record grooves produce capacity variations across the output terminals of the capacity pick-up 4 and in the circuit of the "B. C." oscil-

lator coil across the secondary of the transformer 92 and the tuning condenser 106.

The capacity of the pick-up 4 and/or the lead 28 together with distributed circuit capacity and condenser 106 tune the broadcast oscillator coil to a frequency within the band width of the intermediate frequency and variations in the capacity of the pick-up due to the lateral undulations of the record groove effect a frequency modulation in the output circuit of the tube 36. The doubly tuned resonant coupling circuits of the intermediate frequency amplifier stage or tube 48 are used to demodulate this frequency modulated signal, which demodulation is accomplished due to the selectivity of this I. F. stage. The demodulation of the signal in the I. F. stage results in the production of a signal varying in amplitude at the input of the diode-detector which in conventional receivers is known as the "second detector" in which the signal is rectified and the modulation frequency re-converted to an audio frequency.

The phonograph signals are therefore further amplified by the I. F. stage 48 and are later detected in a diode-detector fed from the doubly tuned transformer coupling 128 and amplified in a subsequent audio amplifier fed from the diode detector. It will be evident that the capacity pick-up 4 effects the frequency of the locally generated oscillations, for this capacity is part of the oscillator tank circuit.

Another method of varying the effective impedance and the resultant frequency of a local oscillator circuit is by means of a variable resistor pick-up as illustrated in Figure 6 by connecting such pick-up and a series condenser in parallel with the oscillator tank circuit capacity as shown in Figure 5. As shown in Figure 6, any suitable conventional small rheostat may have on its resistance adjusting shaft 130 the record traversing needle 16 so that side-to-side or lateral motion of the needle 16 caused by lateral undulations in the record groove effect angular adjustments of the shaft 130 and consequently variations in the resistance of the rheostat 132. One terminal of such resistance pick-up 134 is connected to ground while the other terminal is connected to a condenser 136 which may be mounted on or form part of the pick-up 134.

A wire 138 connects the other side of the condenser 136 to the ungrounded side of the tuning condenser 140 of the oscillator tank circuit, which tank circuit includes the secondary of the transformer 142, the primary of this transformer being grounded at one side and connected by the wire 144 in which is interposed the blocking condenser 146 to the plate of the local oscillator tube 148. The mechanical vibrations of the needle caused by the lateral undulations of the record groove cause variations in the resistance of the rheostat 132. This produces a frequency modulated signal which may be amplified and detected as previously described.

Another method of varying the effective impedance in the local oscillator circuit is by means of a variable inductance pick-up as shown in Figures 8, 9, and 11 connected in a circuit as shown in Figures 7 or 13.

As shown in Figure 8, the variable inductance pick-up 150 may comprise a pair of spaced diaphragms 152 and 154 appropriately mounted in mounting plates 156 and 158. The diaphragms 152 and 154 floatingly support a shaft 160, the shaft extending beyond one of the diaphragms as the diaphragm 152, and having mounted on

or secured to its extending end the record traversing needle 16. The shaft 160 carries a core piece or slug 162 and is positioned within the coil form or cylinder 164 on which is wound or supported a primary coil 166 and an inductively related secondary coil 168. As the needle 16 traverses the record groove, the mechanical to-and-fro movement of the core piece or slug 162 effects corresponding variations in the inductance of the secondary winding. The pick-up 150 may be connected to a local oscillator in a phonograph remote from the radio receiver and the output of this phonograph fed over power lines to a local broadcast receiver, or the local oscillator to which it is connected may be used as the oscillator section of a converter tube forming part of a superheterodyne receiver. One such circuit with which the pick-up may be used is schematically illustrated in Figure 7, wherein it is shown as coupled to a local, electron-coupled oscillator circuit embodying the oscillator tube 170.

The tube 170 may have its plate 172 and its screen grid 174 connected to the positive direct current terminal 176 in the usual manner as by the resistors 178 and 180 and the shunting condenser 182. The control grid 184 of the oscillator tube 170 may be connected to the usual grid condenser 186 which is shunted by the tuning condenser 188 and the grid resistor 190, the common connection of the tuning condenser 188 and the grid resistor 190 being grounded. The wire 192 of a two-wire shielded cable 194 connects the terminal A-2 of the secondary 168 of the inductive pick-up 150 to the common connection of the grid condenser 186 and the tuning condenser 188. The second wire 196 of the two-wire shielded cable 194 connects the common terminal A3 of the primary and secondary windings 166 and 168 to the cathode 198 of the local oscillating tube 170. The other terminal A1 of the pick-up is connected to the shield of the two-wire shielded cable 194, which is grounded as at 200. The out-put of the tube 170 may be fed through the coupling or blocking condenser 202 and may be fed over a power line into a local broadcast receiver or this electron-coupled oscillator circuit may be used as the oscillator section of a converter tube forming part of the usual superheterodyne radio receiver and tuned to the intermediate frequency of the receiver where the signal is further amplified and detected by the usual detector in such receiver.

In the form shown in Figure 9, the inductive pick-up 204 may comprise a single coil winding 206 having the parts 208 and 210 thereof (Figure 10) interconnected as shown in Figure 10, and to the terminals A1, A2, and A3 as shown. The coil 206 may be mounted in any convenient manner as by means of the winding form or cylinder 212 upon the mounting support 214 to which there is secured at one side of the coil a diaphragm 216, the diaphragm being fastened along one edge and free along its opposite edge. The diaphragm 216 has secured at its free edge in any suitable manner the needle 16. The diaphragm also carries a core piece or slug 218 positioned to move into and out of the winding form or cylinder 212 in order to vary the inductance of the coil 206. Thus as the needle vibrates due to the lateral undulations in the record groove being traversed, the inductance of the coil 206 is proportionately varied.

In the form shown in Figure 11, the inductive pickup comprises a primary coil 222 and a sec-

ondary coil 224 similar to the primary and secondary coils 166 and 168 of the pick-up shown in Figure 8. The secondary coil 224 may be mounted as by means of its winding form or cylinder 226 on the mounting support 228. The mounting support 228 has affixed to it a diaphragm 230 similar to the diaphragm 216 of the form shown in Figure 9, the diaphragm 230 having secured to its free edge the needle 16. The diaphragm 230 also carries the primary coil 222 which may be mounted thereon in any suitable manner, as for example, by means of its winding form or cylinder 232. The primary and secondary coils 222 and 224 may be interconnected and connected to the terminals A1, A2 and A3, as shown in Figure 12. The inductive pick-ups 204 and 206 (Figures 9 to 12), may be connected to the local oscillator circuit of Figure 7 in the same manner as illustrated in said figure with respect to the pick-up 150. Whichever form of inductive pick-up 150, 204 or 220 is employed with the circuit of Figure 7, variation in the effective inductance of the pick-up effects the frequency modulation of the locally generated oscillations, which frequency modulated signals may be detected and amplified as previously described.

If the core piece 162 is located on the shaft 160 so as to lie under the primary winding, and used to vary the inductance of that winding instead of the secondary, slight variations in amplitude are produced in proportion to the side-to-side motions of the needle. Such amplitude variations may be employed to control circuits similar to those shown in Figures 14 and 15 and later to be described, for effecting amplitude modulation of the locally generated oscillations. Whether the variations of inductance are used to effect frequency or amplitude modulations of the locally generated oscillations, the out-put signals will pass the usual band width of an intermediate frequency channel of any commercial radio receiver having an intermediate frequency for which the pick-up is designed to produce in combination with other oscillator circuit components, for the side bands are sufficiently close to the carrier or oscillator frequency. The inductive pick-up 150 or 204 or 220 may be connected to the radio receiver part of a combined radio-phonograph as shown in Figure 13. The radio receiver portion of this circuit may be similar to the radio receiver portion of the circuit shown in Figure 4 and the wiper 96 of the switch 32 and the wiper 84 of the switch 78 used to substitute the coils of the pick-up for the broadcast oscillator coils of transformer 92.

Thus with the switch wiper 96 in engagement with the contact 234, the terminal A2 of the coils of the pick-up is connected to the common point of connection between the tuning condenser 106 and the grid condenser 100. At the same time, the terminal A1 of the coils of the inductive pick-up is connected to the wire 235, the contact 238, the wiper 84 of the switch 88 to the wire 80, which is connected to the oscillator anode 42 of the local oscillator or mixer tube 36. Thus with the switch wipers 84 and 96 in engagement with the contacts 234 and 238 the local oscillator circuit is tuned to a frequency within the I. F. band and variations in the inductance of the pick-up provide the frequency modulated signals which are demodulated by the tuned circuits of the I. F. stage of tube 48 and fed to a "second" detector and audio amplifier.

Figure 14 illustrates a form of circuit whereby the capacity pick-up 4 may be used to effect am-

plitude modulation of the locally generated oscillations by effecting a variable feed-back from the plate circuit to the grid circuit. In this form of the invention, the oscillator tube 240 has its plate 242 connected to the positive voltage terminal 244 by the wire 246 and the resistor 248. Signal out-put currents are transmitted through the coupling or blocking condenser 250 and the wire 252. The cathode 254 of the tube 240 is grounded as at 256. The grid 258 of the oscillator tube is connected to the usual grid condenser 260 shunted by the grid resistor 262. The plate circuit is coupled to the grid circuit through the feed-back condenser 264, the capacity of the pick-up and the in-put coil 266 which has its mid-point grounded as at 268 and is tuned by the tuning condenser 270 which is grounded as at 272. Thus as the capacity of the pick-up 4 varies in accordance with the lateral undulations of the record groove, corresponding variations are effected in the feed-back voltage, thus effecting proportional amplitude variations in locally generated oscillations. These amplitude modulated oscillations may be detected and amplified either locally and/or fed over a power line to a local receiver in which the signal is further amplified and reproduced.

Figure 15 illustrates the connection of the resistor pick-up 134 in the feed-back connection of the same oscillator circuit as in Figure 14 to effect amplitude modulation of the locally generated oscillations. The resistance pick-up 134 is thus connected between the condenser 264 and the coil 266. Variations in the resistance of the pick-up 134 as the needle traverses the record grooves effects proportional variations of the feed-back voltage and hence an amplitude modulation of the locally generated oscillations.

It will be apparent from the foregoing description that applicant has provided an improved method and apparatus for reproducing sound from phonograph records or the like.

Applicant has further provided a phonograph record "pick-up" having a higher signal to noise ratio and an improved frequency response to the higher audio frequencies, and improved amplifying circuits controlled by said "pick-up."

The invention has further provided an improved radio phonograph and an improved phonograph pick-up which may be manufactured at materially less cost, but which at the same time possesses greater fidelity and quality in the reproduction of all frequencies within the audio range.

Applicant has further provided in a radio phonograph or a phonograph having electronic amplifying circuits, circuits connecting the phonographic pick-up to the local oscillator of a super-heterodyne radio receiving or reproducing circuit whereby impedance varying phonographic pick-ups may be employed to control the frequency or amplitude modulation of an "intermediate frequency" circuit and the frequency selecting characteristics of the local oscillator in such an intermediate frequency circuit employed to improve the frequency of response of the reproducing circuits to the audio-frequency variations of the sound record.

It is thought that the invention and numerous of its attendant advantages will be understood from the foregoing description and it is obvious that numerous changes may be made in the form, construction and arrangement of the several parts without departing from the spirit or scope of the invention or sacrificing any of its attendant

advantages, the form herein described being a preferred embodiment for the purpose of illustrating the invention.

The invention is hereby claimed as follows:

1. A sound record pick-up comprising a supporting bracket of insulating material, a condenser including a stack of flexible, metal plates with dielectric material therebetween, alternate plates having wings at opposite ends, said bracket and wings being slidably interlocked to yieldably mount said plates on said bracket and a record traversing stylus secured to one of said plates to effect approaching and recessive yielding movements of the plates.

2. A sound record pick-up comprising a supporting plate of insulating material, a condenser including a stack of flexible, metal plates with dielectric material therebetween, alternate metal plates having wings at opposite ends, said insulating plate having spaced openings therein, said wings being slidably interlocked in said openings to yieldably mount said metal plates on said insulating plate, a record traversing stylus secured to one of said metal plates to effect approaching and recessive yielding movements of said plates, an adjustable clamping member passing through

said metal plates, secured to said insulating plate and bearing upon the outer one of said metal plates for adjustment to determine the normal capacity and also the sensitivity of the pick-up.
